UNITED STATES PATENT OFFICE.

LOUIS E. VALCOURT, OF PROVIDENCE, RHODE ISLAND, ASSIGNOR TO LOUIS STERN CO., OF PROVIDENCE, RHODE ISLAND, A CORPORATION OF RHODE ISLAND.

BRACELET HOOK.

Application filed February 7, 1924. Serial No. 691,147.

To all whom it may concern:

Be it known that I, LOUIS E. VALCOURT, a citizen of the United States, residing at Providence, in the county of Providence and State of Rhode Island, have invented certain new and useful Improvements in Bracelet Hooks, of which the following is a specification.

This invention relates to a hook or connector more particularly adapted for attaching the ends of a bracelet to a wrist watch and the like; and the object of this invention is to provide a simple and practical construction of such a hook in which the body and hook portions and the tongue portion are formed of a single piece of stock folded upon itself and the body portion having a housing to inclose and protect a portion of the hook closing tongue.

With this and other objects in view, the invention consists of certain novel features of construction, as will be more fully described, and particularly pointed out in the appended claims.

In the accompanying drawings:

Figure 1 is a side elevation showing a watch and illustrating hooks of my improved construction as attaching the ends of a bracelet to the watch.

Figure 2 is a view showing the blank as cut from sheet stock from which the hook member is formed.

Figure 3 shows the hook in section as formed by folding the blank shown in Figure 2.

Figure 4 is a view of the under side of the hook showing the housing members as folded over the tongue member to inclose a portion thereof.

Figure 5 is a perspective view of the hook.

Figure 6 is a perspective view of one form of chain link which is adapted to be connected to this hook member.

Figure 7 shows the link member in section as connected to the hook member.

With reference to the drawings, 10 designates the body portion of the hook, which has an extending shank bent into hook form 11 at its outer end, the tongue member 12 being folded over to extend through the body of the hook member to normally close the mouth of the hook.

The body portion of the hook is formed by two wings 13 which are folded first on the dotted lines 14 to form side walls 15

and then folded inwardly on line 16 to form a bottom wall 17 to provide a housing for a portion of the tongue member.

The inner end portion 18 of the tongue is offset outwardly to form a shoulder 19 to engage the adjacent edge of the body housing and serve to support the tongue against an excessive end strain on the links of the bracelet.

This loop 20 which serves as a bridge for connecting the shank and tongue portions together, is bent preferably in a semi-circular form to extend beyond the end of the housing sufficiently to provide an opening 21 on its ends to receive the inturned fingers 22 on the next adjacent link 23 of the bracelet.

In order to permit the next adjacent link 23 to be set with its edges abutting squarely against those of the housing body portion 75 of the hook, I have set this loop as at 23 inward so that the edge 25 of the link 23 may abut against this shoulder and the opposite faces of this link may then be formed flush or in the same plane with the corresponding surface of the shank portion 10 of the hook and the bottom wall 17 of the housing.

By forming a housing for the tongue the same is protected for a portion of its length 85 against being inadvertently pressed to unlocked position as the end portion 18 between the end of the housing and the end of the hook only is exposed to be engaged for this purpose. Then again, the side walls 90 of the body housing serve to guide the tongue and hold it in proper position against a lateral strain upon it.

My improved hook is very simple and practical in construction and by making it 95 in a single piece may be manufactured at the minimum cost and it also provides a hook which is very strong and durable in construction.

The foregoing description is directed 100 solely towards the construction illustrated, but I desire it to be understood that I reserve the privilege of resorting to all the mechanical changes to which the device is susceptible, the invention being defined and limited only by the terms of the appended claims.

I claim:

1. A bracelet hook formed of a single piece of sheet stock folded upon itself to 110

provide a body portion with an extending shank having a hook-shaped end and also a resilient tongue member for closing said hook, said body portion having integral 5 folded-up top, bottom and side walls in box-shape formation to inclose and protect that portion of the tongue member extending through said body.

2. A bracelet hook formed of a strip of sheet stock folded upon itself to provide a box-shaped body portion with an extending shank having a hook-shaped end and also a rearwardly extending portion folded to provide a tongue member for closing said hook with an attaching loop at the fold, said tongue having a shoulder normally engaging one of the walls of said box-shaped body to support the tongue against an excessive endways strain on said attaching loop.

3. The combination with a bracelet link, of a bracelet hook formed of a piece of sheet stock folded upon itself to provide a body portion with an extending shank having a hook shaped end and also a resilient tongue member for normally closing the hook, said body portion providing a housing for a portion of the tongue, the folded portion joining the tongue and body form-

ing an eye projecting beyond one end of the 30 housing for receiving means for connecting the hook to the next adjacent bracelet link, said eye being offset inwardly to provide a shoulder to receive the wall edge of the adjoining bracelet link, whereby the outer 35 surface of the link and hook may lie substantially in the same plane.

4. A bracelet hook formed of an integral piece of sheet metal folded upon itself to provide a body portion with an extending 40 shank having a hook-shaped end and also a resilient tongue member for closing the hook by the inherent spring of its stock, said body portion being formed by bent-up 45 walls extending over said tongue to house 45 a portion thereof, the folded portion joining the tongue and body projecting beyond said housing to form a connecting eye, said tongue being offset providing a shoulder 50 to abut against the edge of one of said walls 50 of the body portion when said tongue is in normal position to support the tongue against an excessive endways strain on said connecting eye.

In testimony whereof I affix my signature.

LOUIS E. VALCOURT.
